SCARF PIN AND HOLDER

Charles L. Trout, New York, N. Y., assignor to
Charles L. Trout as trustee

Application October 18, 1934, Serial No. 748,799

11 Claims. (Cl. 24—49)

My invention relates to improvements in cravat holders and has for its chief object the provision of a device which will serve as a cravat holder combined with a scarf-pin or other ornamentation and in which several parts of the device, by being separately secured, one to a cravat and another to a garment, each function as a safety device for the other.

A further object of the invention is the provision of a device which, although secured to a cravat, nevertheless permits all desirable movement thereof with the normal movements of the body while restraining the cravat from objectionable movements.

These objects are achieved by my invention, of which several embodiments are illustrated in the accompanying drawing, wherein

Figure 1 is a front view of one embodiment of my invention, the underlying portions being shown in broken lines.

Fig. 2 is a vertical section on line 2—2 of Fig. 1.

Fig. 3 is a cross-section on line 3—3 of Fig. 1.

Fig. 4 is a front view of a further embodiment of my invention, the underlying portions being shown in broken lines.

Fig. 5 is a vertical section on line 5—5 of Fig. 4.

Fig. 6 is a cross-section on the line 6—6 of Fig. 4.

Fig. 7 is a front view of a further embodiment of my invention, the underlying portions being shown in broken lines.

Similar reference numerals are used to identify similar parts throughout the several figures and in the sectional figures the cravat and garment are shown spaced apart for clearness.

In carrying out my invention, I provide, as shown in Figures 1—3 inclusive, a clasp A which engages the vertical hem D on the shirt front, a scarf pin B which is inserted in the cravat E in the conventional manner and a flexible member C, suitably attached to both the clasp and the scarf pin and adapted to pass around the cravat whereby to hold said cravat in its desired position.

The clasp A is shown as comprising a front plate or bar 1, and a somewhat similar back or underlying plate or bar 2, connected at points intermediate their ends by a hinge 3. These bars are each turned in at one end and are provided on these ends with complementary teeth 4, 4, between which the hem of the shirt is engaged. Between these bars a suitable spring 5 is provided to urge the teeth together whereby to securely hold the clasp on the shirt hem.

The scarf pin B is of a conventional type and comprises a head 6, which may suitably carry a

precious stone or other ornamentation, and a pin 7 soldered or otherwise permanently secured at its upper end to the head 6. The pin 7 is bent at 8 to permit the head to lie neatly against the cravat.

The flexible member C is shown as a doubled chain, connected to the clasp A at the eyelet 9 and to the scarf pin B at the eyelet 10. As thus connected a cravat may pass through the chain between the clasp and the scarf pin.

The device is very easily attached. After the cravat has been properly tied the ends thereof are passed through the chain, with the pin at the front of the cravat. The pin is then inserted in the cravat at the desired point and the clasp, which is under the cravat, is then fastened to the hem of the shirt front, preferably at such a height that the chain will suspend to some extent from both the scarf pin and the clasp.

In the embodiment of my invention illustrated in Figures 4—6, inclusive, I provide a scarf pin B' comprising a substantially horizontal bar 6' as a head and a vertical pin 7' permanently secured thereto, the horizontal bar being slightly longer than the width of the cravat. The flexible member C' is shown as a chain, an intermediate point of which is connected to a clasp or clamp A' at eyelet 9' and the ends of which are connected to the ends of the horizontal bar 6' at eyelets 10'. The clamp A' is a loop of suitable resilient wire material, or the like, bent back upon itself to form two gripping members 11 and 11' adapted to hold the hem of the shirt front between them. In this embodiment pin 7' in addition to being a factor of safety, serves to hold the bar 6' in the horizontal position or at a desired angle. This embodiment is attached in the same manner as the embodiment of Figures 1—3, inclusive.

It will be apparent that in the invention disclosed the scarf pin and the clasp or clamp coact with the flexible member as safety devices for each other, thus minimizing the possibility of accidental loss or of theft; also that the chain, neatly draped from the head of the scarf pin, affords a measure of ornamentation for the cravat.

The embodiment of my invention illustrated in Figure 7 is a structure similar to the embodiment of Figures 4—6, inclusive, from which, however, the pin 7' is omitted. It will be seen that this resulting device would suspend from the clamp A'' with the bar 6'' overlying the cravat E'' and the flexible member C'' substantially underlying the cravat and connecting the ends of the bar to the clamp. This embodiment is adapted to be used as a cravat hold-

er alone and would serve such purpose effectively and present a neat appearance.

My invention is not limited to the particular constructions illustrated herein as it may be modified in various ways without departing from the invention as described and claimed herein.

What I claim is:

1. A cravat holder comprising a flexible member adapted to extend substantially around a portion of a cravat, means for attaching said member to a cravat and means for attaching said member to a garment.

2. A cravat holder, comprising means adapted to extend substantially around a portion of a cravat, a portion of said means adapted to underlie a cravat being flexible and the portion of said means adapted to overlie a cravat being substantially rigid, and means for fastening said flexible portion to a garment.

3. A cravat holder comprising means adapted to extend substantially around a portion of a cravat, a portion of said means being flexible and adapted to underlie a cravat and to be fastened to a garment, and a portion of said means being adapted to overlie the cravat and to be fastened thereto.

4. A cravat holder comprising a pin adapted to be inserted in a cravat, a fastening member for engaging a portion of a garment and a flexible member connecting said pin and fastening member, the connection to the pin being at a portion thereof which does not normally enter the cravat.

5. A cravat holder according to claim 4, wherein the flexible member is of sufficient length to

permit it to extend substantially around a portion of a cravat.

6. A cravat holder according to claim 4 wherein the flexible member is connected to the fastening member intermediate the ends thereof.

7. A cravat holder comprising a bar, a flexible member having its effective ends permanently connected to the bar adjacent the ends thereof and means connected to the flexible member intermediate its effective ends for fastening said flexible member to a garment.

8. A cravat holder according to claim 7, in which the bar has fastening means for fastening it to a cravat.

9. A cravat holder according to claim 7, in which the bar has a pin connected thereto adapted to be inserted in a cravat.

10. A cravat holder comprising a pin adapted to be inserted in a cravat, a fastening member for engaging a portion of a garment and a flexible member connecting the head of the pin and the fastening member, said flexible member being in two portions adapted to pass around opposite sides of a cravat and being connected to the fastening member at a single point thereof.

11. A cravat holder comprising a pin adapted to be inserted in a cravat, a fastening member for engaging a portion of a garment and an endless chain connecting the pin and the fastening member and being so disposed that when the device is worn the chain is connected to the pin at the front of the cravat, thence extends around opposite sides of the cravat and is connected to the fastening member at a single point thereof.

CHARLES L. TROUT.
